UNITED STATES PATENT OFFICE

115,391

DESIGN FOR A COMBINED STOVE, REFRIGERATOR, SINK, AND CABINET

Guyon L. C. Earle, Forest Hills, N. Y.

Application November 26, 1938, Serial No. 81,382

Term of patent 14 years

To all whom it may concern:

Be it known that I, Guyon L. C. Earle, a citizen of the United States of America, residing at Forest Hills in the county of Queens and State of New York, have invented a new, original, and ornamental Design for a Combined Stove, Refrigerator, Sink, and Cabinet, of which the following is a specification, reference being made to the accompanying drawings, forming a part thereof, and in which:

Fig. 1 is a perspective view of a combined stove, refrigerator, sink, and cabinet, showing my new design in closed position; and

Fig. 2 is a perspective view thereof, in opened position.

The present design comprises as the principal and dominating feature thereof a combined structure in which the fronts of all the units comprising the upper portion of the combination are substantially in a plane which is set back from the plane substantially containing the fronts of all the units comprising the lower portion of the combination.

I claim:

The ornamental design for a combined stove, refrigerator, sink, and cabinet, substantially as shown and described.

GUYON L. C. EARLE.
